SOCKET CASING AND SWITCH STRUCTURE

Conrad Laurier Dupuis, Eastview, Ontario, and
Austin Hastie, Carleton Place, Ontario, CanadaApplication August 11, 1947, Serial No. 767,982
In Canada August 12, 1946

2 Claims. (Cl. 200—51.16)

1

This invention relates to socket casings and switch structure more particularly of the type employed for electric light sockets.

In the art of manufacture, socket bodies for electric lights are commonly constructed in two sections in order that the switch unit may be detachably connected to the socket. Apart from the fact that such type of construction requires separately fabricated sections and sectionally formed insulators, the sections require to be secured together by screws or other connecting means. As a result then, structure of that character is frequently difficult to separate or assemble. Further, the cap or cover member, at times, becomes disconnected from the main body and unless restored to its proper position immediately, may result in a short circuit.

One of the objects of the present invention therefore is to avoid and overcome the foregoing and other objections and disadvantages by providing a device of this character wherein the socket body or casing is constructed in single unit form.

Another object of the present invention is to provide a device of this character wherein the insulator for the interior of the socket is in single unit form.

A further object of the present invention is to provide a device of this character wherein the switch lever is maintained in an operative position without the aid of screws or the like.

Still a further object of the present invention is to provide a device of this character wherein the switch lever is not detachable in the "on" or "off" position but may easily and readily be removed for switch removing purposes when required or desired.

Yet another object of the present invention is to provide a device of this character which is novel and simple in form, rugged in nature and one that will the more satisfactorily perform the functions required of it.

Having regard to the foregoing and other objects and advantages which will become apparent as the description proceeds and the details of the invention become known, the device consists essentially in the novel combination and arrangement of parts hereinafter described with more particular detail and illustrated in the accompanying drawings in which:

Fig. 1 is an enlarged elevational view of an embodiment of the present invention.

Fig. 2 is a section taken on the line 2—2 of Fig. 1, with a portion of the socket and insulator being shown in section.

2

Fig. 3 is a plan view of Fig. 1.

Fig. 4 is a side elevational view of the switch operating unit shown partly in section.

Fig. 5 is a plan view of Fig. 4 with the upper insulating disc or block partly broken away for purposes of showing structure therebeneath.

Fig. 6 is a section taken on the line 6—6 of Fig. 4 showing the switch in the "on" position.

Fig. 7 is a view similar to Fig. 6 showing the switch in the "off" position.

Fig. 8 is an elevational view partly in section as seen from substantially the right-hand side of Fig. 4.

Fig. 9 is a section taken on the line 9—9 of Fig. 7.

Fig. 10 is a plan view of the switch lever shown in detached form.

Fig. 11 is a plan view of a modified form of switch lever, and

Fig. 12 is a plan view of a modified form of mounting for the contact brush.

Referring now to the accompanying drawings wherein the present invention is disclosed and wherein like numerals of reference designate corresponding parts in the various illustrations, the numeral 15 indicates the switch housing or casing as a whole while the numeral 16 indicates the switch unit as a whole.

Importantly, the housing or casing 15 comprises a hollow body or shell 17 shaped, spun or molded of any suitable material in single unit form. The base of the casing is provided with an opening 18 for insertion of the electric switch unit while the upper wall is curved inwardly and terminates in a collar with opening 19 for the reception of the well-known insulator 20 and through which the conductor leads pass. An opening 21 is provided in the side wall and it is through this latter opening that the switch lever 22 is adapted to extend to operatively connect the switch operating member later referred to. The lower section of the casing may be provided with a stop shoulder as well as a threaded section 23 for purposes of connecting a lamp shade or the like thereto, if desired.

The switch unit 16 comprises lamp receiving socket or shell 24 threaded as at 25 for detachably connecting an electric lamp (not shown) while mounted on the socket body and secured thereon is an insulating disc or block 26.

Conductively connecting the socket 24 and extending upwardly therefrom is terminal post 27, such post being provided with the well known conductor lead connecting screw 28.

Mounted above the insulating disc or block 26

and in spaced relationship thereto is a further insulating disc or block 29 (see Figs. 4, 5 and 8). This further insulating disc is supported by terminal post 27 and spacer post 30, the post 30 being formed as an integral part of the socket 24 and is provided with an insulator in the form of a sleeve 32.

The lamp contact which is designated by the numeral 33 extends through the insulating disc 26 and terminates on the upper side of the disc in the form of a brush contact 35 while plate 36, provided with terminal screw 37, extends downwardly through insulating disc 29 to provide a brush contact 38 underneath the insulator or disc 29. An insulating disc 39 is disposed upon the upper side of disc 29 for insulating purposes. The spaced contacts 35 and 38, it is observed, are in vertical alignment one with the other on the inner surfaces of the disc members 26 and 29 so that when the contact arm, later referred to, is moved into engagement with such contacts, the switch is in an "on" position and a circuit therethrough completed and when the arm is moved out of engagement with the contacts 35 and 38, the switch is in the "off" position and the circuit is open.

The contact arm just referred to is indicated by numeral 41 and comprises a substantially U shaped member composed of conductive material interposed between disc members 26 and 29 and pivotally mounted therein on pintles 42 and 43 while pivotally mounted to one side of the contact arm is the contact arm operating member 45.

The member 45 previously referred to is pivotally mounted in the disc members by means of pintles indicated at 47 and 48 and is movable back and forth by switch key 22 for purposes of moving contact arm 41 to "on" and "off" position as required. It is also observed that in the normal "on" and "off" positions the member 45 as well as the key 22 are in non-radial alignment with the axis of the body member.

Compression spring 49 (see Figs. 6, 7 and 8), is designed to engage indent 50 formed at the outer end of contact arm 41 while the opposite end of the spring engages the offset tongue 51 of operating member 45. With the arrangement just described and by reference to Figs. 6 and 7, it will be seen that when contact arm or brush 41 is in an "on" or "off" position the spring 49 is beyond "dead center." Thus when member 45 is moved to a point beyond "dead center," the compression spring 49 will force the contact arm 41 either into or out of engagement with contacts 35 and 38 as the case may be. In order to limit travel movement of member 45 during operation, such member is provided with an integrally formed stop pin 53, the pin being movable in the arcuate recess 54 formed in the insulating disc or block 29. Thus as member 45 is moved backward or forward through the operation of the switch lever or key 22, the travel of member 45 is limited by pin 53 engaging the ends of the arcuate recess 54.

In order to disconnect switch lever or key 22 from engagement with operating member 45, the member 45 is moved to a substantially "dead center" position where member 45 with key 22 are out of radial alignment with the body member. When this is accomplished key 22, its engaging recess and the side walls are in parallel and radial alignment with member 45 centrally of opening 21 when the key 22 is removed by an outward pull after which unit 16 is removable as a whole.

As observed in the plan view in Fig. 10, the lever or key 22 is provided with an elongated slot 56 for engagement by the member 45 while the sides thereof are of arcuate form as indicated at 57. The outer ends of the lever are provided with knob like formations 58 while adjacent the outer ends of the surface or face may be roughened or grinded as at 59 to guard against finger slippage.

10. In its normal operative position then lever or key 22 is maintained in engagement with member 45 by reason of its novel position and contour and the fact that in its "on" or "off" position, the slot 56 is parallel with member 45 (see Figs. 6 and 7) but out of radial alignment with the opening 21 in the casing. Thus the key 22 is maintained in engagement with member 45 by its non-radial position with respect to opening 21, plus the arcuate shoulders 57 and the urgency of spring 49.

As more particularly illustrated in Fig. 2, an insulator 60 is provided for the interior of the casing 15 to insulate the switch unit 16 where the casing is constructed of metal. This insulator is of single unit form and covers the entire inner surface of casing and is provided with an opening 61 at its base for the insertion of the switch unit 16, a side wall opening 63 for the reception of the lever or key 22 and a top wall opening 64 through which the conductor leads extend.

Should it become necessary or desirable, the key 22 may be secured to the member 45 by means of a screw or the like. In Fig. 11 therefore the outer end of member 45 is provided with an upturned lip 65 which is engaged by a counter-sunk screw 66.

In the modified form of movable contact brush mounting illustrated in Fig. 12, the inner end of the member 45 is provided with a slot 67, such slot being frictionally engaged by the substantially V shaped end 68 of bar 69, the bar in turn being wound by compression spring 49 which butts the indent 50. The modified forms shown in Figs. 11 and 12 are utilized in combination in order to guard against a "short circuit" through member 66, the bar 69 being constructed of non-conductive material.

From the foregoing it will be seen that we provide a casing or body in single piece unitary form with a single piece unitary insulator lining the interior thereof wherein the switch lever or key is detachably and operatively connected to the switch unit through a side wall opening of the casing without the aid of screws, pins or otherwise and wherein the switch operating lever or key is readily detachable for purposes of removing or replacing the switch unit 16 as a whole.

Many changes may be made in the above and many apparently widely different embodiments may be constructed without departing from the spirit or the essential characteristics of the invention. The present disclosure therefore is intended to be interpreted as illustrative rather than restrictive and that all changes coming within the meaning and range of equivalency of the claims is intended to be embraced therein.

What we claim as our invention is:

1. An electric lamp socket casing and switch structure comprising a unitary hollow switch casing cylindrical shell open at one end and curved over and inwardly and provided with a conductor receiving opening at the opposite end, a lamp receiving socket member endwise removably fitted in the open end and presenting a threaded

opening for reception of a lamp bulb, spaced-apart insulating discs carried at the opposite end of the lamp socket member, a terminal connector on the lamp receiving socket portion, a terminal member carried by one of said insulating discs presenting a central lamp engaged contact within and insulated from the lamp receiving socket member and having a switch contact on the opposite side of the insulating disc, a second terminal connector on the spaced-apart insulating disc having a switch contact opposite the first-mentioned switch contact, said cylindrical shell being provided with a switch lever opening through one side at a location communicating with the clearance between the spaced-apart insulating discs, a switch operating member swingably mounted intermediate its ends between the insulating discs with an outer end presented toward the switch lever opening and with said switch operating member entirely within the confines of the spaced-apart insulating discs to thus permit endwise fitting and removal of the lamp receiving socket member with respect to the cylindrical shell switch casing, a substantially U-shaped contact arm disposed between the insulating discs having pintles at its ends received in bearing openings in said discs with the contact arm swingable to a closed position between the spaced-apart oppositely disposed switch contact portions and to an open position away from said switch contact portions, a spring bearing within

the U-shaped contact arm and at its opposite end against the inner end of the operating member, and a switch lever fitted movably through the opening of the casing removably mounted on the outer end of the switch operating member and retaining the lamp receiving socket and switch structure against endwise removal and displacement from the cylindrical shell casing.

2. The device as set forth in claim 1, wherein the switch operating member is swingably mounted between the insulating discs at a location away from the axial center of the cylindrical shell and near the opening through the side wall thereof, the switch operating lever being provided with arcuate side walls engageable with lateral sides of said opening for retaining said key in the body member in "off" and "on" positions of the switch.
